UNITED STATES PATENT OFFICE

FRANK A. BIEDERMAN, OF CHICAGO, ILLINOIS, ASSIGNOR TO PAPER PATENTS COMPANY, OF NEENAH, WISCONSIN, A CORPORATION OF WISCONSIN

ARTICLE FOR DISPLAY

Application filed February 18, 1932. Serial No. 593,830.

My invention relates to an article of manufacture which is especially suitable for use as an advertising or display medium, as in show windows and in other places, and more particularly relates to an article in the form of a sheet which, when viewed by transmitted light, will present a silhouetted design, which may comprise ornamental or fanciful figures, lettering, and/or other devices, which devices will be invisible in the absence of such transmitted light, as when the sheet is viewed by reflected light.

An object of my invention, therefore, is to provide an article of the class described, which will be inexpensive to manufacture, simple in construction, formed of inexpensive and readily obtainable materials, and which will be highly attractive and generally satisfactory for the purposes in view.

Various other objects and advantages will become apparent as the description proceeds.

Referring now to the drawing illustrating a preferred embodiment of my invention.

Fig. 1 is a plan view of a sheet of material embodying my invention, viewed by reflected light.

Fig. 2 is a similar view of the same sheet, viewed by transmitted light.

Fig. 3 shows an exploded perspective view of the same with the various elements in spaced or dissembled relation, and

Fig. 4 is a sectional view taken on the line 4-4 of Figure 1.

In the preferred embodiment of my invention here illustrated, I form a composite or built-up sheet, the various elements of which are preferably formed of paper or like material. The outermost sheet 10 which directly meets the view of the observer, which may be called the front sheet, may be a creped sheet of medium weight and is preferably of an attractive color, behind which is disposed a layer or sheet 11 of a relatively thin unsized tissue. Behind this tissue sheet is disposed a sheet 12 which is preferably a relatively stiff parchmentized sheet. It will be noted that the three sheets 10, 11 and 12 are corrugated as a unit, and the three sheets may conveniently be corrugated in a single operation.

Arranged to the rear of the corrugated sheets just described is an uncorrugated sheet 15 which may be formed of any suitable material, preferably paper, but in my preferred embodiment is a sheet of creped paper similar to the material of sheet 10. This sheet 15 carries the design, lettering, or other device 16 which it is desired to display in silhouette. The device 16 may be applied as by printing, or the like, to the surface of the sheet 15 which is to be disposed adjacent the sheet 12. Rearwardly of the sheet 15 is a sheet 18, also preferably uncorrugated, which sheet may be formed of fairly heavy stock so as to impart additional body to the composite article.

It is believed that the method of constructing the article will be obvious. As stated above, the sheets 10, 11 and 12 may conveniently be corrugated in a single operation. Glue or other suitable adhesive material may be applied to the rear face of the sheet 12 and, if the sheet 15 bearing the design or device 16 is relatively thin, as is preferably the case, the sheets 15 and 18 may be secured to the corrugated sheets in a single operation, as by passing them through rolls or the like, the adhesive which is applied to the back of the sheet 12 soaking through the sheet 15 and attaching itself to the forward face of the sheet 18.

The use of the article is thought to be obvious. An automatically flashing lamp may conveniently be disposed behind the composite sheet which, when illuminated, shows up the silhouette very clearly, as shown in Figure 2. When the lamp is "out" the silhouette is not visible, as shown in Figure 1.

A very important advantage of the composite sheet embodying my invention is that it is self-supporting in its vertical dimension, largely due to the vertically corrugated construction of the sheets 10, 11 and 12. Thus, a sheet embodying my invention may be used to represent either a plane or curved surface, and due to its corrugated construction may be bent in its horizontal dimension to conform to almost any desired curve, while still retaining its ability to stand upright without any substantial support.

It is also found that the tissue sheet 11 aids very substantially in preventing the design or device 16 from being visible from the front of the composite sheet in the absence of transmitted light.

Various changes coming within the spirit of my invention will doubtless suggest themselves to those skilled in the art. Hence, I do not wish to be limited to the specific embodiment disclosed herein or uses mentioned, except to the extent set forth in the appended claims, which are to be interpreted as broadly as the state of the art will permit.

I claim as my invention:

- 15 1. An article of the class described, comprising a translucent sheet bearing a silhouette, and a translucent vertically corrugated sheet secured in front thereof, said corrugated sheet being sufficiently opaque that said silhouette is substantially invisible therethrough in the absence of transmitted light but is visible therethrough in the presence of transmitted light.
- 20 2. An article of the class described, comprising a translucent sheet bearing a silhouette, and a translucent vertically corrugated sheet secured in front thereof, said corrugated sheet being sufficiently opaque that said silhouette is substantially invisible therethrough in the absence of transmitted light but is visible therethrough in the presence of transmitted light.
- 25 3. An article of the class described, comprising a translucent sheet bearing a silhouette, a relatively stiff sheet secured to the front thereof, and an ornamental front sheet, said front sheet and said stiff sheet being vertically corrugated as a unit and together being sufficiently opaque to prevent said silhouette from being substantially visible therethrough in the absence of transmitted light but being sufficiently translucent to permit its being visible therethrough in the presence of transmitted light.
- 30 4. An article of the class described, comprising a translucent sheet bearing a silhouette, a relatively stiff sheet secured to the front thereof, an ornamental front sheet, and a tissue sheet disposed between said front sheet and said stiff sheet, and said front sheet, tissue sheet and stiff sheet being vertically corrugated as a unit and as a whole being sufficiently opaque to prevent said silhouette from being substantially visible therethrough in the absence of transmitted light but being sufficiently translucent to permit its being visible therethrough in the presence of transmitted light.
- 35 5. An article as defined in claim 3 having a relatively stiff translucent sheet rearwardly of the sheet bearing said silhouette.
- 40 6. An article as defined in claim 4 having a

relatively stiff translucent sheet rearwardly of the sheet bearing said silhouette.

7. A substantially self-supporting article of the class described, formed entirely of paper or the like, comprising a translucent sheet bearing a silhouette, and a translucent vertically corrugated sheet secured in front thereof, said corrugated sheet being sufficiently opaque that said silhouette is substantially invisible therethrough in the absence of transmitted light but is visible therethrough in the presence of transmitted light.

8. A substantially self-supporting article of the class described, formed entirely of paper or the like, comprising a translucent sheet bearing a silhouette, and a translucent vertically corrugated sheet secured in front thereof, said corrugated sheet being sufficiently opaque that said silhouette is substantially invisible therethrough in the absence of transmitted light but is visible therethrough in the presence of transmitted light, said corrugated sheet being sufficiently stiff to support said article.

9. A substantially self-supporting article of the class described, formed entirely of paper or the like, comprising a translucent sheet bearing a silhouette, a relatively stiff sheet secured to the front thereof, and an ornamental front sheet, said front sheet and said stiff sheet being vertically corrugated as a unit and together being sufficiently opaque to prevent said silhouette from being substantially visible therethrough in the absence of transmitted light but being sufficiently translucent to permit its being visible therethrough in the presence of transmitted light.

10. A substantially self-supporting article of the class described, formed entirely of paper or the like, comprising a translucent sheet bearing a silhouette, a relatively stiff sheet secured to the front thereof, an ornamental front sheet, and a tissue sheet disposed between said front sheet and said stiff sheet, and said front sheet, tissue sheet and stiff sheet being vertically corrugated as a unit and as a whole being sufficiently opaque to prevent said silhouette from being substantially visible therethrough in the absence of transmitted light but being sufficiently translucent to permit its being visible therethrough in the presence of transmitted light.

11. An article as defined in claim 9 having a relatively stiff translucent sheet rearwardly of the sheet bearing said silhouette.

12. An article as defined in claim 10 having a relatively stiff translucent sheet rearwardly of the sheet bearing said silhouette.

13. An article of the class described, formed entirely of fibrous material, such as paper or the like, comprising a translucent sheet bearing a silhouette, and a translucent sheet disposed in front thereof, at least one of said sheets being vertically corrugated so as to

render said article substantially self-supporting, said front sheet being sufficiently opaque to prevent said silhouette from being substantially visible therethrough in the absence of transmitted light but being sufficiently translucent to permit its being visible therethrough in the presence of transmitted light.

14. An article of the class described, formed entirely of fibrous material, such as paper or
10 the like, comprising a translucent sheet bearing a silhouette, and translucent sheets disposed in front and rear of said first-mentioned sheet, at least one of which is vertically corrugated so as to render said article substantially self-supporting, the front sheet being sufficiently opaque to prevent said silhouette from being substantially visible therethrough in the absence of transmitted light but being sufficiently translucent to permit its being
20 visible therethrough in the presence of transmitted light.

In testimony whereof, I affix my signature.
FRANK A. BIEDERMAN.
